UNITED STATES PATENT OFFICE.

ALBERT E. SIERAD AND MILTON SIERAD, OF NEW YORK, N. Y., ASSIGNEES TO GEORGE W. BUTTON CORPORATION, OF NEW YORK, N. Y., A CORPORATION OF NEW YORK.

DESIGN FOR A BOTTLE.

Application filed April 9, 1929. Serial No. 30,820. Term of patent 3½ years.

To all whom it may concern:

Be it known that we, ALBERT E. SIERAD and MILTON SIERAD, citizens of the United States of America, residing at New York, in the city, county, and State of New York, have invented a new, original, and ornamental Design for a Bottle, of which the following is a specification, reference being had to the accompanying drawing, forming a part thereof.

In the drawing,

Fig. 1 is a perspective view of our bottle, and

Fig. 2 is a top view thereof.

We claim:

The ornamental design for a bottle substantially as shown.

ALBERT E. SIERAD.
MILTON SIERAD.
